UNITED STATES PATENT OFFICE.

JOHN LOCKEN, OF COMSTOCK, MINNESOTA.

REGRINDING AND REBORING MACHINE.

Application filed July 30, 1923. Serial No. 654,711.

To all whom it may concern:

Be it known that I, JOHN LOCKEN, a citizen of the United States, and a resident of Comstock, in the county of Clay and State 5 of Minnesota, have invented certain new and useful Improvements in Regrinding and Reborning Machines, of which the following is a specification.

This invention relates to a re-boring and 10 re-grinding machine and has for its object the provision of a device which is ordinarily employed in re-boring but which may be readily converted into a device for re-grinding operations.

Another object of the invention is the provision of a device which is simple in construction and effective for alternate re-grinding and re-boring and which may be 15 readily and easily converted from one to the other.

This invention will be best understood from a consideration of the following detailed description in view of the accompanying drawing forming a part of the specification; nevertheless it is to be understood that 20 the invention is not confined to the disclosure, being susceptible of such changes and modifications which shall define no material departure from the salient features of the 25 invention as expressed in the appended claims.

In the drawings:

Figure 1 is a longitudinal section of a device constructed according to my invention.

Figure 2 is a fragmentary longitudinal section of a removable tubular bearing sleeve for supporting a re-grinding head.

Figure 3 is a vertical section taken along the line 3—3 of Figure 1.

Figure 4 is a vertical section taken along the line 4—4 of Figure 1.

Figure 5 is an end view partly in section showing the adjustment of the shaft.

Figure 6 is a view in detail of the removable connections for the re-boring shaft and the re-boring cutters.

Figure 7 is a plan view of the closure cap for the removable bearing tube.

Referring to the drawings, 1 designates a table having an elevated portion 2 which is hollowed out longitudinally for receiving a removable tubular bearing sleeve or re-boring shaft 3. Upon the portion 2 is mounted an electric motor 4 having the short end 5 of a shaft projecting beyond the

same which is removably connected with a driving shaft 6, by means of an enlargement 7.

Upon the shaft 6 and driven thereby is 60 a pulley 8 which has a guideway in its hub engaging a key 9 on the shaft 6 and by which the pulley is fastened to the shaft and rotated by said shaft but is permitted to move upon the same when desired. 65

Upon the inner end of the sleeve 3 and where said sleeve is reduced is secured the lower end of a racket 10. The lower end of the bracket is enlarged as shown at 11 and provided with a semi-circular socket engaging the reduced end of the sleeve 3. A clamping member 12 which is drawn to the member 11 by bolts locks the bracket to the end of the sleeve. The upper end of the bracket is provided with a yoke 13 having 70 pins 14 projecting inwardly for engaging at diametrically opposite points a groove 75 formed in the hub of the pulley 8.

Mounted upon the outer end of the table is a second bracket 16 having a yoke 17 with 80 threaded pins 18 having a threaded engagement with perforations in the said yoke for clamping the bearing 19 in position. The end of the shaft 6 is of cylindrical formation and is mounted in the bearing 19. A counter 85 shaft 20 mounted centrally of the tubular sleeve 3 is provided with ball bearings 21 and 22 of the double row type for supporting the shaft centrally of the hollow sleeve 3. A third ball bearing 23 is located on the 90 inner end of the counter shaft and said shaft at this point has rigidly mounted thereon a pulley 24 driven by a belt 25 which is connected with the pulley 8.

A cap closure 26 (shown more particularly in Figure 7) is bolted to the outer end of the sleeve and engages the bearing 23 to prevent the loss of lubricant from the hollow sleeve. Shoulders 27 formed in the sleeve 3 engage the respective bearings 21 and 22 to prevent 100 slippage of the same. The cap closure 26 likewise is adapted to lock a curved bracket member 28 to the end of the sleeve 3.

A rod 29 has its inner end swiveled in a 105 perforation in the free end of the bracket 28, and is adapted to feed the grinding head into an engine cylinder which is being reground.

A second shaft 30 is mounted in the outer 110 end of the hollow sleeve 3 and has a removable connection with the counter shaft 20, the connection comprising an enlarged por-

tion 31 with a squared passage which receives the squared end of the shaft 20. Screwed upon the outer end of the sleeve 3 is a second sleeve 32 alined with the sleeve 3 and providing a bearing for the re-grinding head shaft 33. A grinding head 34 is mounted on the outer end of the shaft and abutting the end of the conical bearing 35. A bushing 36 is mounted in the bearing 35.

10 The conical bearing is adjustable as shown more particularly in Figure 5 having a screw 37 so that when the bearing is turned the grinding head 34 may be located in eccentric relation with the shaft 20 and thereby provide for re-grinding the larger bores in cylinders. The scale 38 determines the depth of the boring.

15 A yoke 39 formed at the end of the table 1 is adapted for supporting the work operated on. It will be noted that not only the shaft 30 and the re-boring section at the end of the tubular sleeve 3 are removable from the table but the sleeve 3 is bodily removable and carrying with it all the operating parts located therein as a unitary structure by loosening the bolts of the clamping member 12 and by removing the cap 26.

20 A member 40 connects the shaft 30 with the grinding head shaft 33. The inner end of the shaft 33 is provided with an enlargement 41 having a squared passage therein adapted to receive the squared end of the shaft 42 formed integrally with the connecting member 40. The member 40 is provided with a squared passage adapted to receive the squared end of the shaft 30. By this means a flexible connection is provided between the shaft 30 and the shaft 33 so that when the adjustment is made 25 through the screw 37 no strain will be thrown upon the shaft 30 when rotating.

25 A sleeve 43 spaces the roller bearings 22 from the roller bearing 23 mounted within the sleeve 3.

30 As shown in Figure 6 a connection 32^b is provided which is adapted to be screwed on the threaded portion 45^a of the shaft 3 by means of the threads 45 formed on the inner wall of a recess in the member 32^b. Said member is provided with a threaded reduced portion 44 upon which the cutter heads for the re-boring operation are screwed. When the connection 32^b is placed 35 on the end of the sleeve 3 the bearing sleeve 32, together with the connection 40 and shaft 42 and related parts connected with the grinding head 34, are removed. A worm gear 46 mounted upon the end of a drive sleeve is adapted to engage the worm 47 on sleeve 3 for rotating said shaft at about 36 revolutions per minute when the device is employed for re-boring. For re-grinding the motor 4 operates shaft 6, belt 25 and shaft 20.

35 A hand wheel 43 is adapted to drive the rod 29 inwardly and cause sleeve 3, together with the bracket 10 and pulley 8 to be move inwardly for moving the re-grinding head 34 at a predetermined speed into the work which is being operated on. The hand wheel is likewise operated for moving the shaft 3 inwardly when the device is used as a re-boring machine for moving the cutter heads into a cylinder.

40 On the face plates 39^a the work is adapted to be clamped in the usual manner. It will be noted that both sleeve 3 and shaft 20 may be operated simultaneously but at different speeds. The re-grinding shaft 20, together with the head, is adapted to be rotated at approximately 5500 revolutions per minute. The shaft 30 revolves only the grinding wheel 34 while the sleeve 3 is employed in revolving the grinding head within the cylinder when the grinding head is in an offset position according to the adjustment shown in Figure 5 so that it may follow the cylinder walls of any sized bore.

45 What I claim is:

1. In a re-grinding and re-boring machine, a table, a tubular bearing member extending longitudinally of the table, a shaft extending longitudinally of and having bearings in the tubular member, a second shaft 50 removably mounted in the tubular member and removably connected with the first mentioned shaft, driving means mounted on the table, a shaft removably mounted on the table and rotated by the driving means, operative connections between the last mentioned and the first mentioned shafts, a bracket mounted on the inner end of the tubular bearing member, a cap for closing the inner end of said bearing member and secured to said end for aiding in locking the bracket in position, said bracket adapted to support the driving connection between the driving shaft and the first mentioned shaft in position.

55 2. In a re-grinding and re-boring machine, a table, a tubular bearing member extending longitudinally of the table, a shaft extending longitudinally of and having bearings in the tubular member, a second shaft 50 removably mounted in the tubular member and removably connected with the first mentioned shaft, driving means mounted on the table, a shaft removably mounted on the table and rotated by the driving means, operative connections between the last mentioned and the first mentioned shafts, said operative connections comprising a pulley provided with a grooved hub 60 slidably mounted on the driving shaft and rotatable therewith, a pulley on the first mentioned shaft operatively connected with the pulley on the driving shaft, a bracket mounted on the inner end of the tubular bearing member and provided with a fork 65 at its upper end having pins engaging the

groove in the hub of the first mentioned pulley for maintaining said pulley in alignment with the pulley on the first mentioned shaft.

5 3. In a re-grinding and re-boring machine, a table, a tubular bearing member extending longitudinally of the table, a shaft extending longitudinally of and having bearings in the tubular member, a second shaft removably mounted in the tubular

member and removably connected with the first mentioned shaft, driving means mounted on the table, a shaft removably mounted on the table and rotated by the driving means, operative connections between the last mentioned and the first mentioned shafts, and a bracket removably connected to the tubular member and providing a support for the last mentioned shaft. 15

JOHN LOCKEN.
